WILLIAM C. MUENCH, OF INDIANAPOLIS, INDIANA, ASSIGNOR TO PROGRESS MACHINE CO., OF INDIANAPOLIS, INDIANA, A CORPORATION.

BOTTLE-FEEDING MECHANISM.

1,128,030.

Specification of Letters Patent.

Patented Feb. 9, 1915.

Original application filed May 6, 1912, Serial No. 695,498. Divided and this application filed March 9, 1914.
Serial No. 823,540.

To all whom it may concern:

Be it known that I, WILLIAM C. MUENCH, a citizen of the United States, and a resident of Indianapolis, county of Marion, 5 and State of Indiana, have invented a certain new and useful Bottle-Feeding Mechanism; and I do hereby declare that the following is a full, clear, and exact description thereof, reference being had to the accompanying drawings, in which like letters 10 refer to like parts.

This application is divided out of my previous application Serial No. 695,498, dated May 6, 1912, for bottle feeding mechanism.

The object of the invention is to provide means in connection with a bottle crowning or capping machine for the accurate feeding of bottles thereto, the feeding mechanism being controlled by the crowning and capping mechanism so that the bottle will be fed to the latter at exactly the right time.

The features of the invention will be understood from the accompanying drawings 25 and the following description and claim.

In the drawings, Figure 1 is a perspective view of the upper part of the crowning head machine with the lower and other parts omitted. Fig. 2 is a plan view of a 30 part of the same with parts removed. Fig. 3 is a plan view of the star wheel. Fig. 4 is a section on the line 4—4 of Fig. 3.

In detail there is shown in the drawings 35 a bottle crowning machine of well known construction having a hopper 12 from which the caps or crowns are fed through a guide 13 to the crowning heads 14 as they are moved to the proper position. The bottles to be crowned are placed upon the upper 40 end of the plungers or bottle supports 15, each of which lies immediately below one of the crowning heads 14.

For the purpose of feeding the bottle to the crowning machine, a star wheel 16 is 45 mounted on a vertical shaft 18 and slightly above the crowning machine table 17 and upon the upper end of said shaft, a star wheel 19 is secured which meshes with the crowning heads 14. The star wheel 16 is 50 thus caused to revolve in time with the plungers 15 and the crowning heads 14. Upon the lower end of the shaft 18 and below the table 17 a bevel gear 20 is secured with which a bevel gear 21 upon the horizontal

shaft 22 meshes, see dotted lines in Figs. 2 55 and 3, and upon the outer end of said shaft, projecting through the front face 23 of the table 17, a sprocket wheel 24 is secured. A shaft 25 lies parallel with the shaft 22 and upon its outer end carries a sprocket wheel 60 26 which is driven from the sprocket 24 by a chain 27. Upon the inner end of the shaft 25, the driving pulley, not shown, of the conveyer belt 8 is secured for delivering the bottles to the star wheel 16. The loose 65 pulley of the belt conveyer 28 is mounted as desired.

The star wheel 16 is shown in detail in Figs. 3 and 4. Said wheel has a top plate 30 with peripheral notches 31 therein and 70 U-shaped plates 32 of the same shape as the notches secured upon the under side of the top plate. A collar 33 is secured centrally of the top plate by means of which the star wheel is mounted upon the shaft 18. 75

A curved guide plate 34 is removably secured to the crowning machine table 17 by means of bolts 35 extending through slotted extensions 36 from said plate. Said plate is secured substantially concentric with the 80 star wheels 16 and extends thereabout substantially 90 degrees and the lower left hand end extending over the path of the plungers 15 is cut away sufficiently to clear the crescent shaped stops 37 on said plungers 15. A 85 curved guide plate 38 is pivotally secured to the right hand end of the guide plate 34 and the free end thereof is normally caused to bear against the conveyer guide 39 by a spring 40 secured to the guide 34 and bearing against the guide 38.

The operation of my invention is as follows: The crowning machine being driven in the usual manner the star wheel 16 and belt conveyer 28 will also be driven and the 95 filled bottles delivered by hand or otherwise to the conveyer will be carried toward the star wheel 16 and will be caught between the projections thereon and will be carried to the left in the direction of the arrow, see 100 Fig. 2, and delivered to the bottle holders or plungers 15 of the crowning machine after which they will be crowned in the usual manner. Should a bottle from the conveyer meet one of the projections on the star wheel instead of moving into the notch it will be carried to the left, but the guide 105 38 will yield and the bottle will not be

broken but will be yieldingly held until the next notch on the star wheel comes opposite to the bottle when it will be forced into said notch by the spring 40 bearing on the 5 guide 38. The action of the spring 40 and plate is always to move the bottle in a reverse direction to the movement of the star wheel 16 and never in the same direction. Breakage is thus prevented. As the bottle is 10 moved by the star wheel it will be given a twisting motion upon the table 17 and will be delivered to the center of the plungers 15. This adjustment is very important for should the end of the guide 34 be set too 15 near the star wheel 16, the bottle will be caught and crushed against the plunger stop 37. On the other hand, should the guide 34 be set too far out the bottle will not be properly centered against the plunger stop 20 37 and when the plunger is raised, the neck of the bottle will hit against the crowning head and will be broken. In practice it has been found necessary not only to adjust the guide 34 for each different size of bottle 25 used, but for bottles of the same volume made by different manufacturers as well. As the bottles are moved onto the bottle holders the necks pass into the notches of a guide wheel 142 which is secured to the 30 main column 41 of the machine and revolute therewith and as the bottles are discharged from the bottle holders, the guide wheel will steady the necks and keep them

from falling. To accomplish this result the discharging faces of the guide wheel arms 35 are curved away from the direction of rotation so that the bottles will be discharged with a gradually decreasing movement and with no sudden jar or fling. The bottles are discharged by the centrifugal movement 40 of the rotary table 42 and wheel 142.

I claim as my invention:

A bottle crowning machine including a fixed table, a rotary table thereon, a circular series of crowning heads above said rotary 45 table, a circular series of bottle holders vertically movable through said rotary table, and beneath the crowning heads, a conveyer for conveying the bottles to said fixed table, a star wheel on said fixed table between the 50 conveyer and the series of bottle holders for transferring the bottles from the conveyer to the bottle holders, a bottle guide substantially concentric with said star wheel, a shaft for said star wheel, and a second star 55 wheel on said shaft meshing with the series of crowning heads and whereby said star wheels are actuated.

In witness whereof, I have hereunto affixed my signature in the presence of the wit- 60 nesses herein named.

WILLIAM C. MUENCH.
